UNITED STATES PATENT OFFICE.

WILLIAM E. WHITE, OF CHICAGO, ILLINOIS, ASSIGNOR TO KALMAN STEEL COMPANY,
OF CHICAGO, ILLINOIS, A CORPORATION OF DELAWARE.

SCREED CHAIR.

Application filed January 3, 1927. Serial No. 158,624.

My invention relates to concrete construction accessories, and particularly to a chair adapted to support a screed or surface-determining member.

5 One of the objects of my invention is to provide a screed chair of extremely light and economical skeleton construction, adapted for use in supporting a screed with the purpose of allowing the chair to remain 10 in the concrete. A device of this character should be of such a construction that the concrete flows through and around it, in order to avoid lines of cleavage, and of such economical construction that it may be allowed 15 to remain in the concrete as a part thereof.

A further object is to provide a structure of the character described which may be folded into very small compass adapting it 20 for shipment without bulkiness or difficulty in handling.

The invention will be more readily understood by reference to the accompanying drawings, in which:

25 Fig. 1 is a side elevation showing a pair of my improved skeleton screed chairs in operative position;

Fig. 2 is an end view thereof;

Fig. 3 is a plan view, and

30 Fig. 4 is an enlarged side view showing the device in folded form.

A screed or levelling bar is indicated at A, the bar being intended to serve as a means for levelling and fixing the height of the upper surface of the finished concrete, and being intended to be removed after such levelling has been accomplished. The bar is supported in a seat, 10, provided in the transverse member 11, of an inverted U-shaped 35 support, preferably composed of wire. The legs, 12, of the support terminate in feet, 13 that rest on the form indicated at B.

A pair of braces are provided, each consisting of a U-shaped or V-shaped section of 40 wire, 14 in the ends of which eyes 15 are formed, which embrace the legs, 12 in such manner that the braces are permitted pivotal movement; that is, they are enabled to swing into the operative position shown in Figs. 45 1 to 3, or into the folded position shown in Fig. 4. When in operative position, nails or staples, 16, are applied at the angles of the brace for fastening them to the form. Pref-

erably the parts will be so constructed that the legs occupy a slightly inclined position, 55 as shown. This insures that a vertical line through the center of gravity will fall between the supports and result in a stable structure even without the fastening nails.

In order to prevent upward movement of 60 the braces I may flatten the wire composing the legs at a point above the upper eye, thus forming laterally projecting lugs, 17.

Devices such as shown are of very simple 65 and economical construction, may be quickly and easily applied and may be shipped without occupying undue space.

Obviously modifications may be made in the construction here disclosed without departing from the spirit of my invention, and 70 I do not wish to be limited except as indicated in the appended claims.

I claim:

1. In combination, an inverted U-shaped support having a seat in its upper end and a 75 U-shaped brace pivoted to one leg of said support and adapted to occupy a position at right angles thereto.

2. In a screed chair, the combination of a 80 support comprising a pair of legs having a connecting top member providing a seat for a bar, and a U-shaped lateral brace, pivoted to one leg of the support.

3. In a screed chair, the combination of an 85 inverted U-shaped wire member having a seat formed in the member connecting the legs thereof, and a U-shaped wire brace pivoted to one of the legs of said wire member with capacity for swinging movement therearound.

4. In a screed chair, the combination of an 90 inverted U-shaped support and a pair of U-shaped brace members pivoted to the legs of said support and adapted to occupy positions at right angles to the support and to be swung into folded position relative to said support.

5. In combination, an inverted U-shaped 95 support composed of wire and providing a seat for a screed, and a pair of wire braces, each pivoted at two points to a leg of said support and adapted to be swung into operative and folded positions.

In testimony whereof I have affixed my signature.

WILLIAM E. WHITE.
